UNITED STATES PATENT OFFICE.

LAURENCE P. SAUNDERS, OF LOCKPORT, NEW YORK.

PROCESS AND MEANS FOR ADJUSTING TAPPETS ON INTERNAL-COMBUSTION ENGINES.

Application filed August 4, 1922. Serial No. 579,738.

To all whom it may concern:

Be it known that I, LAURENCE P. SAUNDERS, a subject of the King of Great Britain, residing at Lockport, in the county of Niagara and State of New York, have invented certain new and useful Improvements in Processes and Means for Adjusting Tappets on Internal-Combustion Engines; and I do hereby declare the following to be a full, clear, and exact description of the invention, such as will enable others skilled in the art to which it appertains to make and use the same.

This invention relates to a method and means of adjusting tappets on internal combustion engines, and has for its object to provide facilities which will enable a single person to adjust said tappets with certainty and more expeditiously than has heretofore been proposed.

With these and other objects in view, the invention consists in the novel procedure, and in the novel details of construction more fully hereinafter disclosed and particularly 25 pointed out in the claims.

Referring to the accompanying drawings forming a part of this specification, in which like numerals designate like parts in all the views:

30 Figure 1 is a diagrammatic sectional view illustrating a tappet to be adjusted to a valve stem and valve operated by said tappet;

35 Figure 2 is a diagrammatic sectional view illustrating a pair of tappets similar to the one illustrated in Figure 1, which control valve stems of a slightly modified form of construction;

40 Figure 3 is a diagrammatic sectional view taken on the line 3—3 of Figure 2, looking in the direction of the arrows, and illustrating the adjustment of one of the tappets shown in said figure;

45 Figure 4 is a sectional view taken on the line 4—4 of Figure 2, looking in the direction of the arrows; and

Figure 5 is a perspective view of a peculiar form of wrench employed in the adjustment of the tappets.

50 1 indicates the body of an internal combustion engine, 2 the intake passage, 3 a valve having a stem 4 controlling said passage, 5 a guide for said stem and 6 a spring to return the valve to its seat 7 after it has been lifted. As is well known, it is customary to lift valves such as 3 from their

seats by means of tappets 8 reciprocating in guides 9 and having slightly convex ends 10. These tappets are moved by cams 11 mounted on shafts 12, which cams are provided with portions 13 that move the tappets at a slow speed and portions 14 that move said tappets at a high speed. The extreme lower ends 10 of the tappets are made convex to cause them to revolve under 65 the action of the cams and thus prevent the latter from wearing grooves in said ends. In order to adjust the space between the upper end of the tappet and the lower end of the valve stem, it is customary to 70 insert the screw threaded adjustable member 14' into the upper end 15 of the tappet, and to lock it in place as by the lock nut 16. Such being the usual construction, it is clear that should the valve seat 7 become 75 coated with carbon as often happens in practice, or should the rotation of the tappet by the cam serve to shorten the total length of the tappet, or should the space when the valve is seated between the extreme 80 upper end 18 of the tappet and the extreme lower end 19 of the valve stem be increased from any cause whatever, as it often is, in practice, then the extreme end 18 of the tappet will be suddenly forced by the cam 85 11 against the extreme end 19 of the valve stem, and a constant knocking or tapping noise will be heard by the operator, which as is further well known, constitutes a signal to adjust the tappets.

90 By the present methods, if one is to adjust the tappets of an internal combustion engine, he must with one wrench 20, Figure 3, hold fast the head 18 of the screw threaded member 14', he must then with 95 a second wrench 21 seize the lock nut 16, and he must with a third wrench (not shown), seize the tappet body to prevent its turning while the lock nut 16 is loosened and the head 18 adjusted. It will thus be 100 seen that the requirement of the use of these wrenches is a vexatious one, and the adjustment of tappets by a single person is rendered very difficult as well as tedious.

According to my invention, on the other 105 hand, tappets can be quickly and efficiently adjusted by a single person who proceeds as follows: Knowing that the portion 13 of the cam called the "quiet zone" does not lift the tappet with sufficient suddenness to cause 110 an objectionable knocking or pounding on the valve stem end 19, the operator knows

it will be sufficient if he so adjusts the total length of the tappet that when its convex surface 10 contacts with said quiet zone its top surface 18 will contact with the low end 19 of the valve stem when the valve is seated. He then takes the wrench 25 which is made of sheet metal, and which is provided with the two notches 26 and 27, and he straddles with one of said notches 26 the 10 squared or cut away portions 30 of one tappet 8, and he straddles the squared portion 31 of another tappet 33 with the other notch 27. That is to say, he takes advantage of the fact that there are a plurality 15 of tappets and valve stems located side by side on internal combustion engines, and he slips his wrench 25 over a pair or a plurality of the squared portions of these tappets in order to lock them from turning and 20 to leave both of his hands free to manipulate the other wrenches 20 and 21. A plurality of tappets such as 8 and 33 having thus been locked against turning by a plurality of notches 26 and 27 spaced apart 25 the same distance that separates the tappets to be adjusted, the operator next turns the cam 11 until the surface 10 of the tappet 8 rests upon the cam 11 at a point separated from the quiet zone 13. His hands being 30 free he next by the aid of the wrenches 21 and 20 so manipulates the locknut 16 and head 18 that when the valve is seated the head 18 contacts with a strip of metal known as a "feeler" which is held against the end 35 19 of the valve stem, and which is indicated by dotted lines at 20'. The particular thickness of the feeler 20' to be used is well known and is determined by the engineering departments of the firms making the 40 cams. The operator next sets up on the lock nut and secures the parts in their adjusted positions. Should the other tappets such as 33 need adjustment, the same operation is carried out with respect to them.

45 It will now be clear that my invention comprises a procedure by which two or more tappets are locked against turning while unscrewing a lock nut and causing

one end of one tappet to rest on the cam 11 at a point outside the quiet zone, and then 50 so adjusting the other end of said tappet that it will contact with a feeler 20' placed between said last named tappet end and the extreme lower end 19 of the valve stem when the valve is seated after being cleaned.

55 It is obvious that those skilled in the art may vary the details of the procedure without departing from the spirit of the invention, and therefore, I do not wish to be limited to the above disclosure except as may be required by the claims.

60 What is claimed is:

65 1. The process of adjusting, in an internal combustion engine, a tappet provided with an adjustable portion secured by a lock nut and located adjacent another tappet, which consists in locking both of said tappets against rotation on their axes while leaving them free to slide longitudinally; causing the quiet zone of the cam operating the tappet to be adjusted to contact with the lower end of said last named tappet; moving the valve operated by said last named tappet to be seated; loosening said lock nut; 70 moving the operating end of said adjustable portion of the tappet into contact with the end of the valve stem while the valve is seated; and securing said adjustable portion in its new position, substantially as described.

75 2. In an internal combustion engine, the combination of a plurality of valves having depending stems; a plurality of rotatable tappets located side by side having flattened portions and adjustable end portions adapted to contact with said valve stems; a plurality of cams to operate said tappets; and a locking means adapted to fit said flattened portions to temporarily lock against rotation a plurality of said tappets while the length of one of the latter is being adjusted to operate its corresponding valve stem, substantially as described.

80 In testimony whereof I affix my signature.

LAURENCE P. SAUNDERS.
